SUCTION ROLL

Earl E. Berry, Beloit, Wis., assignor to Beloit Iron Works, Beloit, Wis., a corporation of Wisconsin

Original application September 9, 1935, Serial No. 39,679. Divided and this application December 24, 1936, Serial No. 117,465

7 Claims. (Cl. 92—53)

This invention relates to suction rolls and more specifically relates to suction rolls having a plurality of separate suction areas.

This application is a division of my copending application entitled: "Vacuum forming paper making machine," Serial No. 39,679, filed September 9, 1935, now Patent No. 2,154,719 granted April 18, 1939.

It is an object of this invention to provide suction rolls having a plurality of separate suction areas.

A further object of this invention is to provide a suction roll having a suction area that is readily adjustable to vary the size thereof.

15 A further object of this invention is to provide a suction roll wherein a suction mandrel extends concentrically through a perforated roll and communicates with the inner periphery of the roll along separate areas thereof.

20 A further object of this invention is to provide a suction roll with three separate suction areas each having a separate passageway for drainage from the roll.

A further object of this invention is to provide 25 a suction roll having a stationary mandrel extending concentrically therethrough and mounted on its ends on supports having drain conduits communicating with the mandrel.

A further object of this invention is to provide 30 a suction roll wherein the suction applied to the roll and the drainage through the roll are separately controlled.

A specific object of this invention is to provide 35 a suction roll with an adjustable suction area adapted to be regulated in size without disassembly of the roll.

Other and further objects of this invention will 40 become apparent to those skilled in the art from the following detailed description of the annexed sheets of drawings which disclose preferred embodiments of the invention.

On the drawings:

Figure 1 is an end elevational view of a suction drum construction and mounting therefor 45 according to this invention.

Figure 2 is a side elevational view of the apparatus shown in Figure 1.

Figure 3 is a broken top plan view of the apparatus shown in Figures 1 and 2.

50 Figure 4 is an enlarged vertical cross-sectional view taken substantially along the line IV—IV of Figure 2.

Figure 5 is a fragmentary vertical cross-sectional view taken substantially along the line 55 V—V of Figure 4.

Figure 6 is an enlarged fragmentary vertical cross-sectional view of the top portion of the suction roll of this invention showing the top suction area thereof and the means for adjusting the size of this area.

Figure 7 is an enlarged fragmentary vertical cross-sectional view of the suction roll showing the lower suction area and the means for adjusting the size of this area.

Figure 8 is a cross-sectional view taken substantially along the line VIII—VIII of Figure 6, with parts omitted, and showing an end of the suction roll with means for sliding the suction seal to vary the suction area.

Figure 9 is an end elevational view taken substantially along the line IX—IX of Figure 8.

As shown on the drawings:

In Figures 1 to 5 inclusive, the reference numeral 10 designates a perforated metallic cylinder disposed concentrically around a metal mandrel 11 which is secured at its ends in end supports 12. The mandrel 11 is bolted by bolts 13 into the annular recesses defined by flanges 12a of the end supports 12 as shown in Figure 5.

As shown in Figures 4 and 5, the mandrel 11 is provided with three rows of openings, 14, 15 and 16 disposed along one side thereof. It should be understood that the openings can be disposed along any portion of the periphery of the mandrel. Partition walls 17 and 18 are provided in the mandrel to define three separate chambers 19, 20 and 21 therein as shown in Figure 4. Each of these chambers 19, 20 and 21 communicates with a separate row of the openings 14, 15 and 16.

The end supports 12 for the mandrel are likewise provided with partitions 22 and 23 to define three separate passageways 24, 25 and 26, as shown in Figure 4, communicating with the passageways 19, 20 and 21 respectively. The passageways 24, 25 and 26 of each end support are 40 connected with pipes 27, 28 and 29 respectively for receiving the liquid drained into the passageways.

Each passageway 24, 25 and 26 is provided with a baffle such as 30 (Figure 5) forming a 45 separate passageway 30a therein. The baffle 30 extends above the level of liquid flowing from the mandrel 11.

As shown in Figures 1 to 4, suction pipes 31, 32 and 33 communicate with the passageways 30a in the passageways 24, 25 and 26 respectively of the end supports 12. Valves 31a, 32a and 33a (Figure 1) regulate the relative degree of suction in the pipes 31, 32 and 33. Liquid drained from the passageways in the mandrel 11 flows 55

through the passageways 24, 25 and 26 into the pipes 27, 28 and 29 while air is sucked through the openings 14, 15 and 16 in the mandrel, through the passageways 24, 25 and 26 with the drainage liquid and is then drawn into the suction pipes 31, 32 and 33 behind the baffles 30. By this arrangement a very high vacuum can be obtained and the degree of vacuum can be separately regulated in each of the three passages in the supports and mandrel. The drain pipes 27, 28 and 29 may also be connected with suction pumps to effect a forced drainage of the liquid from the mandrel.

The perforated cylinder or roll 10 is bolted at one end thereof, as shown in Figure 5, to a large gear 34 by means of bolts 35. The gear 34 has a solid web portion 36 closing the space between the mandrel 11 and the roll 10. A shoulder 37 is formed on the inside face of the gear 34 and the end of the roll 10 fits snugly over the shoulder 37.

The inner edge of the web portion 36 of the gear 34 defines an annular bushing 38 which is slipped over the mandrel 11.

25 A bearing sleeve 39 is secured around the mandrel 11 by means of pins 40 in spaced concentric relation to the bushing portion 38 of the gear 34.

A bearing ring 41, preferably of bronze, is fitted around the sleeve 39. The bearing ring 30 41 has an outturned flange 42 at its outer end thereof. An end thrust ring 43 is secured to the mandrel 11 in abutting relation to the flange of the bearing ring 41. The gear 34 and the roll 10 secured thereto can thus freely rotate over the bearing ring 41 while the end thrust ring 43 holds the roll against longitudinal movement.

If desired, the shoulder 37 and the bushing 38 provided on the gear 34 may be separate from the gear in the form of a separate chime ring. 40 Such a chime ring can be used at the other end of the roll 10.

On each side of each row of openings 14, 15 and 16 of the mandrel 11 there are formed on the mandrel outturned flanges 50, 51, 52 and 53 as 45 shown in Figure 4. These flanges are spaced concentrically from the outer periphery of the mandrel 11 as shown. The flanges 50 and 51 have bolted thereon angle members 54 and 55 respectively carrying sealing strips 54a and 55a in their vertical legs for rubbing against the interior of the roll 10 to define a suction area "A" on the roll 10.

The horizontal leg of the angle member 54 may be slotted as at 56 (Figure 6) for receiving bolts 55 such as 57 therethrough. The member 54 can thus be slid over the flange 50 by loosening the bolts 57 to adjust the position of the strips 54a against the roll 10. This adjustment, however, can only be made when the mandrel 11 is removed from the perforated roll 10.

The flange 52 likewise has bolted thereon an angle member 58 carrying a sealing strip 58a in its vertical leg for rubbing against the inner periphery of the roll 10. The sealing strips 55a of the angle member 55 and 58a of the angle member 58 define a suction area B on the roll 10.

The flange 53 has bolted thereon another angle member 59 carrying in its vertical leg a sealing strip 59a for rubbing against the inner periphery of the roll 10 and defining with the strip 58a of the angle member 58 a suction area C on the roll.

To make it possible to vary the sizes of the suction areas A, B, and C without removing the mandrel from the roll, the angle members 55 and 75 59 carried by the flanges 51 and 53 of the man-

drel are adjustable on the flanges from outside of the roll 10.

The angle members 55 and 59 have the horizontal leg portions thereof curved to fit on the flanges 51 and 53 and these portions are provided with slots 60 and 61 respectively as shown in Figures 6 and 7. Bolts 62 and 63 extend through the slots 60 and 61 and are threaded into the flanges 51 and 53 respectively. Coiled springs 64 and 65 are disposed around the bolts 62 and 63 and held under compression between the heads of these bolts and washers 66 and 67, which washers are disposed around the bolts and fit over the horizontally curved legs of the angle members. The angle members 55 and 59 are thus held tightly against the flanges 51 and 53 but are adapted to be slid along these flanges because of the resilient spring retaining means.

The ends of the suction areas A, B, and C are sealed by annular sealing strips 70 (Figure 5) adapted to rub against the inner periphery of the roll 10. These sealing strips 70 are carried by ring members such as 71 which are bolted to an outturned flange 72 of the mandrel 11 by means of bolts 73. It should be understood that a sealing strip is positioned near each end of the mandrel 11, thereby sealing the ends of the suction areas A, B, and C.

As shown in Figures 8 and 9, the mandrel 11 has formed thereon a pair of supports 74 and 75 spaced from each other opposite the angle member 55 but outside of the end sealing ring 71. A similar pair of supports is formed opposite the angle member 59.

As shown in Figure 9, the supports 74 and 75 receive therebetween a horizontal bolt 76 which is rotatably mounted at its ends in the supports. The bolt is provided with a head 77 adapted to be engaged by a wrench for rotation.

A boss 78 is threaded on the bolt 76 and carries a rod 79 projecting through a slot 80 formed in the vertical portion of the sealing member 71. The rod 79 extends into a well 81 (Figure 8) formed in the angle member 55 and is secured therein by means of a pin 81a.

As shown in Figure 5 the roll 10 is rotatably supported around the mandrel 11 by means of the gear 34 at one end thereof. The opposite end of the roll, however, is supported on a chime ring 82 as shown in Figures 8 and 9. The chime ring has a shoulder portion 83 for receiving the end of the roll 10 and the roll is bolted to the ring by means of bolts 84. The inner portion of the chime ring 82 forms an annular bushing 85 in spaced concentric relation around the mandrel 11. A bearing sleeve 86 is pinned around the mandrel 11 by means of pins 87 and receives therearound another bearing sleeve 88 which is disposed within the bushing 85 of the chime ring.

An end thrust ring 89 abuts the sleeves 86 and 88 and is held on the mandrel 11 by means of pins 90 thereby holding the roll against longitudinal movement relative to the mandrel.

The chime ring 82 is provided with openings such as 91 therethrough at points opposite to the angle members 55 and 59. These openings can be closed by plates 92 as shown in Figure 8.

Removal of the cover plate such as 92 makes it possible to insert a wrench for engagement with the head 77 of the bolt 76 to rotate the bolt for moving the boss 78 along the bolt to thereby slide an angle member such as 55 or 59 along its flange 51 or 53. In this manner the suction areas A, B, and C can be varied in size without disassembly of the roll.

From the above descriptions it should be understood that the suction rolls of this invention comprise a suction mandrel having independent drainage passageways for liquid communicating with variable sized areas on a perforated roll rotatably mounted on the mandrel. Suction can be applied to any of these areas in regulated amounts and separate passageways are provided for air drawn through the suction areas and liquid drained through these areas. The perforated roll is supported by the mandrel and the mandrel is carried in end supports having passageways communicating with the mandrel passageways. The sizes of the suction areas can be regulated without disassembly of the structure thereby providing a construction capable of wide usage to meet variable demands on paper machines and the like apparatus wherein suction rolls are used.

I am aware that many changes may be made and numerous details of construction may be varied through a wide range without departing from the principles of this invention, and I, therefore, do not purpose limiting the patent granted hereon otherwise than necessitated by the prior art.

I claim as my invention:

1. In a hollow suction roll, a suction mandrel having an opening formed in the periphery thereof, a perforated drum rotatably mounted around said mandrel in spaced concentric relation therefrom, means for draining and evacuating the interior of said mandrel, seals extending longitudinally on said mandrel adjacent the sides of said opening for defining a suction area on the drum, end seals interposed between the mandrel and drum, one of said end seals having a slot cut therethrough, a longitudinal pin extending transversely through said slot and secured to one of the longitudinal seals, and means for moving said pin laterally for sliding the seal along the mandrel toward and away from the other longitudinal seal to vary the width of the suction area.

2. A suction roll comprising a pair of end supports in space opposed relation having a plurality of passageways formed therein, an open ended hollow cylinder secured at its ends to said end supports and having a plurality of passageways therein each in communication with a passageway in the end supports, ring members rotatably mounted on said cylinder, a perforated roll disposed concentrically around said cylinder in spaced relation therefrom and secured to said ring members, means for rotating said roll relative to the cylinder, said cylinder having openings in the periphery thereof communicating each passageway therein with the perforated roll, seals extending longitudinally on the cylinder alongside of each of the openings therein, packing material carried by said seals for cooperating with the interior of the perforated roll to define separate suction areas for each passageway in the cylinder on the perforated roll, annular seals disposed around the cylinder for sealing the ends of the suction area, means extending through said annular seals engaging some of the longitudinal seals, and a screw device arranged transversely of said means engaging said means to move the means and longitudinal seals circumferentially of the mandrel whereby said longitudinal seals can be moved relative to the cylinder toward and away from each other to vary the widths of the suction areas defined thereby without disassembly of the suction roll.

3. In a suction roll, in combination, an open ended cylindrical mandrel having an opening through the wall thereof intermediate the ends of the mandrel, a perforated roll disposed around the mandrel, rings secured to the ends of the roll rotatably carrying the roll on the mandrel in spaced concentric relation therefrom, one of said rings having an opening therethrough communicating with the space between the mandrel and roll, a closure plate for said opening, an annular end seal fixedly carried on said mandrel for sealing the space between the mandrel and roll, said end seal having an elongated slot therethrough in alignment with said opening through the ring member, a longitudinal seal carried on said mandrel and extending along one side of the opening therein, a pin secured in said longitudinal seal and extending through the slot in the end seal, and mechanism between the end seal and the ring in alignment with the opening through the ring for moving said pin laterally to slide the longitudinal seal relative to the mandrel without removal of the end seal.

4. A suction roll comprising a hollow cylindrical suction mandrel having an opening through the side thereof, a perforated roll rotatably mounted around the suction mandrel, end seals between the mandrel and roll for sealing the space between said roll and said mandrel at the ends of said opening in the mandrel, a longitudinal seal mounted on said mandrel on each side of said opening and extending between said end seals for defining a suction area on said perforated roll, means on the outside of the mandrel extending through one of the end seals and secured to one of said longitudinal seals, and a device for moving said means circumferentially of the mandrel from outside of said end seal for positively sliding the longitudinal seals connected with the means toward and away from the other longitudinal seals to vary the size of the suction area without disassembly of the roll structure.

5. A suction roll comprising a hollow suction mandrel, means for supporting the mandrel, said mandrel having an opening in the side wall thereof, a perforated roll rotatably mounted around the mandrel, a pair of longitudinal seals carried by the mandrel and extending between the roll and mandrel on each side of said opening to cooperate with the roll for defining a localized suction area on the roll, at least one of said seals being movably mounted on the mandrel, a device secured to said movably mounted seal, and mechanism for positively laterally moving said device to positively slide the seal on the mandrel toward and away from the other seal for varying the width of the suction area.

6. A suction roll comprising a hollow suction mandrel, means for supporting the mandrel, said mandrel having an opening in the side wall thereof, a perforated roll rotatably mounted around the mandrel, end seals between the mandrel and roll to seal the space between the roll and mandrel at the ends of the opening, one of said end seals having an opening therethrough, longitudinal seals carried by the mandrel between the roll and mandrel on each side of said opening to cooperate with the roll for defining a localized suction area on the roll, at least one of said longitudinal seals being movably mounted on the mandrel, a device secured to said movably mounted longitudinal seal extending through said opening in the end seal, mechanism for positively laterally moving said device to positively slide

- the longitudinal seal on the mandrel toward and away from the other longitudinal seal for varying the width of the suction area, and a cover for closing the opening in said end seal
- 5 5 to seal the space between the longitudinal seals and end seals from the atmosphere, whereby a removal of said cover and manipulation of said mechanism will vary the width of the suction area without disassembly of the roll structure.
- 10 7. A suction drum construction comprising an imperforate open ended hollow cylinder having an opening along the side wall thereof, end supports receiving the ends of the cylinder in airtight relation, a passageway in at least one of
- 15 said end supports communicating with the in-

terior of the cylinder, a perforated drum rotatably mounted around said cylinder and carried by the cylinder, longitudinal seals disposed between the cylinder and drum and carried by the cylinder on each side of said opening to define a suction area on the drum, at least one of said longitudinal seals being slidably mounted on the cylinder, a device carried on said cylinder at the end of said slidably mounted longitudinal seal, means connecting said device with said seal and 10 manually operative mechanism on said device to move said means laterally for sliding the movable seal toward and away from the other seal to vary the width of the suction area.

EARL E. BERRY. 15
